JAMES A. GRAY, OF SAN FRANCISCO, CALIFORNIA, ASSIGNOR TO AMERICAN CAN COMPANY, OF SAN FRANCISCO, CALIFORNIA, A CORPORATION OF NEW JERSEY.

MECHANISM FOR COMPRESSING CAN-BODIES.

1,140,676.

Specification of Letters Patent.

Patented May 25, 1915.

Application filed April 16, 1914. Serial No. 832,259.

To all whom it may concern:

Be it known that I, JAMES A. GRAY, a citizen of the United States, residing in the city and county of San Francisco and State of California, have invented certain new and useful Improvements in Mechanism for Compressing Can-Bodies, of which the following is a specification.

The present invention relates to an apparatus for preparing can bodies for shipment, whereby the can body after being operated thereon will be in a substantially flat condition which will permit a greater number to be stored in a case of a given size than would be possible were the same in a cylindrical form.

The invention has for its principal objects to provide an apparatus by the use of which all bodies operated upon will be compressed to a uniform size, one which will operate on the bodies as fast as the same are fed thereto, one which is automatic in its operation of compressing the bodies and discharging the same in their compressed condition, and one by the use of which the bodies to be compressed will be rapidly operated upon, thus reducing the cost of compressing the bodies and increasing the capacity of the machine.

With the above mentioned and other objects in view the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more fully comprehend the invention, reference is directed to the accompanying sheet of drawings, wherein—

Figure 1 is a view in side elevation of my invention, disclosing the supporting frame, the reducing matrix and the conveying means associated therewith. Fig. 2 is a longitudinal sectional view disclosing more fully the shape of the reducing matrix, and illustrating a can body being received in one end of the apparatus in a cylindrical form and a can body being discharged from the

apparatus in a compressed form. Fig. 3 is an end view of the discharge end of the machine disclosing the final compressing rolls and a can being discharged therefrom. Fig. 4 is a sectional view taken on line $x-x$ of Fig. 2, and viewed in the direction of the arrow.

Referring more particularly to the drawings, wherein like characters of reference designate corresponding parts throughout the several views, the numerals 1 designate the side members of a supporting frame 55 arranged in parallel spaced relation to each other, and formed at their opposite ends with the upstanding portions or arms 2 and 3, and said side members are connected by the end members 4. Rotatably mounted in journals in the arms 2 is the transversely disposed drive shaft 5, which carries a suitable compressing roll 6 between the arms 2, and said shaft carries at one end a cog wheel 7 which intermeshes with a corresponding cog 8 carried by a shaft 9 rotatably mounted in bearings in the arms 2 above the shaft 5, and said shaft carries a suitable compressing roll 10 which is in slight spaced relation above the roll 6. The drive shaft 5 carries 70 on its opposite end from the cog 7 a drive wheel 11 which is adapted to receive its power from any suitable source.

The central portion of the respective compressing rolls 6 and 10 is cut away as at 75 12 and 13 for the reception of the respective endless conveying belts 14 and 15, which extend at their opposite ends over the respective idlers 16 and 17 mounted on shafts 18 and 19 rotatable in bearings in the arms 80 3. The idlers 16 and 17 are both cut away as at 20 and 21 to receive the belts 14 and 15 and the idler 16 is in a plane substantially level with the compressing roll 6 so that the belt 14 is substantially level, and the 85 idler 17 is positioned in a plane a slight distance above the compressing roll 10, that the conveying belt 15 will be downwardly inclined toward the compressing roll 10.

A reducing matrix or frame extends from 90 a point adjacent the idlers 16 and 17 to a point adjacent the final compressing rolls 6 and 10, and said frame assists in reducing the cans as conveyed therethrough by the belts 14 and 15 toward the final compressing 95 rolls 6 and 10. The reducing matrix or

frame consists in the parallel extending side members 22 supported at their opposite ends on the arms 2 and 3 by the securing bolts 23, and secured to said side members 5 adjacent their ends are the rectangular supporting frames 24 and 25, the frame 25 positioned adjacent the final compressing rolls being of a considerable smaller area than the frame 24 which is adjacent the receiving end of the machine. Suitable upper and lower boards or plates 26 and 27 secured adjacent their opposite ends to the upper and lower interior faces of the frames 24 and 25 extend parallel with and in close proximity to the outer faces of the conveying belts 14 and 15 which move in a direction toward the final compressing rolls 6 and 10. The ends of the boards or plates 26 and 27 terminate short of the compressing rolls 6 and 10 and idlers 16 and 17.

It will be apparent that as a can body is fed onto the belt 14, the same is conveyed by the belts 14 and 15 toward the final compressing rolls 6 and 10, and as 25 conveyed the can body is gradually reduced from a cylindrical to an oval body between the boards 26 and 27 and is prevented from rolling movement or displacement therefrom by the side members 22. As the can 30 body is conveyed by the belts 14 and 15 beyond the end of the boards 26 and 27 it is in a substantially flat condition and is engaged by the portions of the compressing rolls 6 and 10 adjacent the cut-out portions 35 12 and 13, is finally compressed thereby and is then discharged in a compressed or substantially flat condition from the machine to be packed ready for shipment.

I have provided a device which is capable of receiving and uniformly compressing a quantity of can bodies at one time, one which is automatic in its operations after the bodies have been fed thereto, and one from which the can bodies are discharged after being compressed.

Having thus described my invention what I claim and desire to protect by Letters Patent is:—

1. A machine of the class described, the 50 same comprising a tubular rigid reducing matrix through which the can bodies are propelled, a conveyer associated with said matrix for propelling the can bodies therethrough, certain of the opposing walls of 55 said matrix converging in a direction from the inlet toward the discharge end thereof for the compressing of the can body as propelled through the matrix.

2. A machine of the class described, the 60 same comprising a tubular rigid reducing matrix through which the can bodies are propelled, a conveyer associated with the matrix for propelling the can bodies therethrough, certain of the opposing walls of 65 said matrix converging in a direction from

the inlet toward the discharge end thereof, and compressing means associated with the discharge end of said matrix for acting on the compressed can bodies as discharged therefrom.

3. A machine of the class described, the same comprising a tubular rigid reducing matrix through which the can bodies are propelled, a conveyer associated with the matrix for propelling the can bodies therethrough, certain of the opposing walls of 70 said matrix converging in a direction from the inlet toward the discharge end thereof, and compressing rolls associated with the discharge end of said matrix and between 75 which the compressed can bodies pass after which the compressed can bodies pass after being conveyed through said matrix.

4. An apparatus for converting cylindrical can bodies into a substantially flattened condition for shipment, the same comprising an open rigid non-traveling reducing instrumentality, mechanism for conveying can bodies therethrough, and means associated therewith for receiving the partially flattened bodies discharged therefrom 80 for finally compressing the same.

5. An apparatus for the described purpose, the same comprising an open, tapering rigid matrix for gradually compressing a cylindrical can body into a substantially 95 flattened condition, and mechanism associated therewith for delivering and conveying can bodies through said means.

6. An apparatus for the described purpose, the same comprising an open, rigid 100 matrix for receiving and gradually compressing a cylindrical body into a substantially flattened condition, and rotary means associated therewith for receiving therefrom the can body and completing the compression thereof.

7. An apparatus for the described purpose, the same comprising a rigid open tapering reducing member for compressing cylindrical can bodies into substantially flattened condition, means for conveying the can bodies therethrough, and associated mechanism for receiving the partially flattened bodies and giving final compression thereto.

8. A machine of the class described, the same comprising an open, rigid matrix for compressing a substantially cylindrical can body into a substantially flat form, means for delivering can bodies to be compressed 110 to said compressing means and for conveying the compressed can bodies therefrom, and means for receiving the compressed can bodies from the compressing means for finally compressing the same.

9. A machine of the class described, the same comprising a rigid, open tapering matrix for gradually compressing a substantially cylindrical can body into substantially 120 oval form, of means working within the 125

matrix for receiving and conveying can bodies to be compressed therethrough, and rotary means associated with the matrix for receiving the can bodies therefrom and giving final compression thereto.

10. A machine of the class described, the same comprising an open, rigid tapering tubular reducing matrix through which the can bodies are propelled, certain of the opposing walls of said matrix converging in a direction from the inlet toward the outlet thereof, and an endless conveyer operating longitudinally within said matrix for conveying the can bodies through the same.

11. A machine of the class described, the same comprising an open, rigid tapering tubular reducing matrix through which the can bodies are propelled, certain opposing side walls of said matrix converging in a direction from the inlet toward the outlet opening thereof, a pair of compressing rolls at the discharge end of said matrix, and between which the compressed cans pass after leaving the discharge end of said matrix.

25 means for rotating said rollers, an endless conveyer operating over each of said rolls and each passing through said matrix adjacent said converging walls for conveying the can bodies from the feed end of said matrix through the same to the discharge end thereof, and an idler for supporting the opposite end of each endless conveyer.

12. In a machine of the class described, the same comprising an open, rigid tapering

tubular reducing matrix, certain of the opposing walls of said matrix converging in a direction from the inlet toward the outlet thereof, a pair of compressing rolls adjacent the discharge end of said matrix and between which the can bodies pass after leaving the discharge end of said matrix, and a conveyer for the can bodies extending through said matrix and between said rolls.

13. An apparatus for the described purpose, the same comprising an open, rigid tapering means for receiving and gradually compressing can bodies into substantially a flattened condition, and instrumentalities associated therewith for propelling can bodies through said compressing means.

14. An apparatus for the described purpose, the same comprising an open, rigid tapering structure composed of horizontally disposed bottom and side members and a horizontally disposed downwardly inclined top member, flexible means traveling within and through said structure, and associated instrumentalities situated at the discharge end of the frame structure for receiving and finally compressing the discharged can bodies.

In testimony whereof I have signed my name to this specification in the presence of two subscribing witnesses.
